PLASTERING SYSTEM

Marcus M. Cory, San Diego, Calif.

Application September 22, 1936, Serial No. 101,953

8 Claims. (Cl. 72—130)

This invention relates generally to methods of and means for forming plaster or cement walls and ceilings, including solid as well as hollow types of both outside and inside walls. The invention is particularly applicable to formation and finishing of the outside of outer plastered or stucco walls and ceiling, though cement or other materials may be handled according to the same process, and will be understood to be included within the scope of the invention and of the appended claims.

The primary object of the invention is to provide an extremely rapid and at the same time inexpensive method of forming walls and ceilings of plaster, cementitious, and similar materials, and of forming ornamental beads or moldings, if desired, in the same operation, or by themselves.

In accordance with the invention, there is provided a comparatively large smooth plane surface or trowel, and means whereby this trowel may be moved and guided along the surface of the wall to be constructed. The plaster is placed from a position to the rear of the wall being formed by hand or with use of mechanical means such as a cement gun, against the surface of this trowel. The trowel is intermittently or slowly moved along the plane of this wall, and the plaster is placed against it and built up to requisite thickness. The moving trowel finishes the surface of the plaster so placed against it, and is passed but once over the wall surface. Solid or cored walls may be formed by the use of two such trowels moved along as the wall is built, which finishes both wall surfaces at one operation. In this case the cementitious material is placed between the two trowels or finishing surfaces from above or from the open side.

As a modification which is useful in some circumstances, paper or cloth is so placed that it acts as the finishing mold and lies between the plaster being placed and the form or trowel which is moved along back of the point of placement and holds the paper or cloths firmly in the proper place during the shooting or placement. Sometimes it is advantageous to have this paper in a roll on the back side of the trowel and lead it from the roll across the face of the form, the paper being fastened to the plaster or cement at the starting corner. The paper is allowed to remain on the plaster until thoroughly set and is then removed. Different textures of finish are obtained by using different textures of paper. In certain instances, forms corresponding to impressions desired in the surface are fastened to the paper and leave their imprint in

the surface. Also, in some instances, blocks of tile or other particles are placed in the surface of the plaster or cement by first pasting them on the paper or cloth, and which thus become imbedded in the wall surface.

Various objects and features of the invention will appear and be made apparent in the following detailed description of present illustrative forms of the invention, reference for this purpose being had in the accompanying drawings, in which:

Fig. 1 shows the upper portion of the exterior wall of a two-story building being plastered in accordance with the present invention;

Fig. 2 is a view of the lower portion of the same exterior wall;

Fig. 3 is a vertical section taken on line 3—3 of Fig. 1;

Fig. 4 is a vertical section taken on line 4—4 of Fig. 2;

Fig. 4a shows a modification of trowel guiding means;

Fig. 5 is a rear elevational view of the trowel;

Fig. 6 is a view taken as indicated by line 6—6 of Fig. 5;

Fig. 7 is a view showing a modification;

Fig. 8 is a view taken on line 8—8 of Fig. 7;

Fig. 9 is a view showing a further modification;

Fig. 10 is a view taken on line 10—10 of Fig. 9; and

Fig. 11 is a view showing a still further modification, in which both surfaces of a wall are formed and finished in the same operation.

Referring first to Figs. 1 to 7, inclusive, I indicate generally at 10 an unfinished building being plastered in accordance with the present invention, Figs. 1 and 3 showing the upper portion of the building and Figs. 2 and 4 showing the lower portion of said building. In said views foundation walls are indicated at 12, lower and upper floor joists are indicated at 14 and 15, respectively, concrete floor slabs are shown at 16, flooring at 16a, and ceilings at 17. Wall studding (of wood or steel) is indicated at 19, and at 19a are indicated framing members surrounding the window openings. Wire mesh reenforcing for the plaster is indicated at 21, being shown as stretched over columns 11 and studding 19.

The invention is here illustrated as applied to a building having a fire wall or parapet 25, and the reenforcing wire mesh 21 is shown as stretched up over the top of the inner frame work of said fire wall and down back of its inner surface, as clearly indicated in Fig. 3. The reen-

forcing screen is also stretched within the window openings defined by members 19a, as indicated in Fig. 4.

The vertical plane of the outer surface of the wall to be constructed is indicated in Figs. 3 and 4 at W. A large finishing form or trowel 30, in the present instance of substantially the vertical dimension of a story of the building, is positioned with its inner vertical finishing surface 31 in wall plane W. Though this trowel member may be mechanically constructed in various ways, I here show a preferred construction in which the trowel is made up of a series of horizontally extending sections 32 placed edge to edge and connected at the back by suitable frame work. For instance, as shown in Figs. 5 and 6, the back surface of each trowel section 32 is provided with a pair of spacer members 33. Angle irons, such as indicated at 34 and 35, are screwed to these spacer members, as by screws 36 to secure adjacent sections together. To enable readily changing the number of trowel sections used, these angle irons are preferably used in pairs, comprising upper members 34 and lower members 35, the upper and lower members of each pair being arranged with their flanges 37 in engagement with one another as shown in Fig. 5. These engaging flanges are secured together by bolts 38. It will be evident that the trowel may be assembled with different numbers of trowel sections depending upon the extent of overlap of angle irons 34 and 35.

For the specific use illustrated in Fig. 3, the trowel is formed at the top in such a manner as to extend over the top of and behind fire wall 25, as indicated at 40.

Guide means are provided for the trowel whereby the trowel is movable in a horizontal direction in the plane W of the wall surface to be formed. For instance, the trowel shown in Figs. 1 and 3 is provided at the bottom with rollers 42, supported on mountings 43 on the lower ends of its angle irons 35, which run in a track 45 mounted on brackets 46 temporarily secured to the building structure, as by being bolted to vertical columns 11. The other horizontal edge of the trowel, which in the instance of Figs. 1 and 3 overhangs fire wall 25, is likewise provided with rollers 48 running in a track 49 supported by the building structure. These tracks and rollers support the trowel with its smooth surface 31 in plane W, and guide the trowel for horizontal linear movement in said plane.

The leading and trailing edges of the trowel are beveled or rounded as at 39a, and the surface 31 of the trowel is usually as smooth as possible. In some instances it is desirable to increase the smoothness of the trowel by the use of oil, wax, etc., and in certain instances I may face the trowel with suitable materials such as vulcanized rubber, etc.

The plastering operation is carried on as follows: The trowel is first positioned on its tracks at one end of the surface to be plastered, for instance at the left-hand end of the wall surface shown in Fig. 1. The plaster is then placed against this trowel from the rear, and this is preferably, though not necessarily, done with a plaster or cement gun 60, of any known or appropriate type, in the hands of the plasterer (see Fig. 3). When a reinforcing screen or mesh is used, the plaster is thus shot from the gun through such screen and against surface 31 of the trowel, and is so built up to the wall thick-

ness desired. The plaster thus shot or placed against the trowel is indicated at P in Fig. 3.

When the surface 31 of the trowel has been nearly covered with plaster, and the plaster has been built up to the thickness desired, a second operator moves the trowel forwardly on its tracks. In so moving, the trowel finishes the surface of the plaster already placed, and also keeps up with the plasterer handling the gun. Thus, the plasterer handling the gun works along the wall, building up the wall to proper thickness from bottom to top, and the trowel is moved just sufficiently fast to keep up with the plastering operation, the trowel always presenting a backing-up surface against which the plaster is discharged. It will be evident that the trowel may be moved continuously or intermittently, though in either event the average speed of the trowel must be such as to keep abreast of the plastering operation. Thus the traveling trowel finishes the entire wall surface, and at the same time serves as a backing for the plaster which is being placed or shot from the back side of the wall.

Sometimes it is desirable to allow the plaster to partially or wholly set before moving the trowel, in which case more than one trowel may be used on the work. The operators after placing cement back of one trowel, go to another and another and the first one is moved just before the man with the cement gun gets ready for it in its new position. In such a case, of course, the trowel members may not be moved in the plane of the wall surface.

The trowel preferably passes but once over the wall surface, and it will be evident that by this method a plaster or cement wall may be constructed with great rapidity.

A convenient means for moving the traveling trowel is indicated in Fig. 1 of the drawings. A cable 62 is attached to the trowel, as in the manner illustrated, and this cable is passed over a guide pulley 63 and down to a winding mechanism 64 turned by the second operator.

Figs. 2 and 4 show the second stage in the plastering of the side wall of the two-story building illustrated in the drawings. The trowel 30 in this instance is flat from top to bottom, except for the curvature at its leading and trailing edges.

The track 46a at the bottom is the same as before. The upper track and guide roller, however, support and guide the trowel from the back. Thus, angle irons 34 carry rearwardly extending rollers 67 which engage in a track 68 carried by a bracket 69 supported by false work generally indicated at 70. The track and rollers at the lower edge of the trowel carry the weight of the trowel, while track 68 and rollers 67 back up the trowel and hold it up to wall plane W. The trowel is of sufficient height to overlap and engage a portion of the outer surface of the previously laid second story half of the wall, and this engagement holds the trowel against tilting inwardly. In plastering a one-story building or wall surface, the track and rollers at the lower edge of the trowel are duplicated at the upper edge of the trowel, as indicated at 42b and 46b, respectively, in Fig. 4a.

Where the height of a vertical wall requires more than one level of placement, as in Figs. 1 to 4, it is generally preferable to place the top level first and to work downwardly. This procedure keeps the work cleaner, and the joints between successively laid sections will slope in the

proper direction to prevent leakage through the wall from rain, etc.

The window and door openings are treated in the following manner. A separate form is used for each of the surfaces not in the large wall plane to be formed by the large moving mold or trowel. For instance, as indicated in Fig. 4, a box 75 is built and placed in the window opening, its top 76, bottom 77 and sides 78 being spaced within the previously mentioned window framing members 19a. This opening form or box extends out to the finished surface plane W, and the back of the form is closed, as at 80, to keep out the plaster. The plaster is filled in between this form and framing members 19a, as indicated at 81, thus providing plaster window opening surfaces 82.

It will be evident that the mold or trowel may be of any size or shape appropriate to the work to be done, and that it may be positioned and guided to handle surfaces other than vertical wall surfaces, as for instance ceilings. A given trowel of the construction described is adjustable to work of different types and sizes simply by removing or adding sections, which are held together by the rigid frame members 34, 35.

Moldings, beads fillets, etc., where desired, are formed either by themselves or simultaneously with the wall surface, by use of a special trowel section having the form desired. Thus, the trowel in Fig. 3 is shown provided with sections 86 formed at 87 to provide ornamental molding 88 near the upper edge of the wall surface.

Figs. 7 and 8 show a modification of the method, in which a roll of paper 90 is mounted on the back surface of the trowel, near its leading edge, the roll being mounted on a vertical axle 91 supported by brackets 92 secured to the trowel. The paper 90a from the roll is led from the roll around the leading edge of the trowel and across its face, and is fastened, as at 93 (Fig. 8), at the beginning end of the wall to be formed. This paper unrolls as the trowel moves, and is allowed to remain on the plaster or cement until thoroughly dry, and is then removed. This paper is of use with plasters and cements of certain kinds of consistencies, and is useful in protecting against the sun and too rapid drying. Different textures of finish are obtained by using different papers of different textures. Moreover, in certain instances, impressions desired in the surface are applied to the paper and so imprinted on the wall surface. If desired, the layer of paper 90a adhering to the wall surface may of course be drawn off and rolled back up on the roll on the back of the trowel, the trowel simply being moved in reverse direction on its tracks as the paper is re-rolled. It will also be evident that the paper may be used without necessarily sup- 60

plying it from a roll mounted on the trowel; broadly, any manner of placing a suitable flexible sheet of paper, or any suitable equivalent, in the plane of the wall surface will serve.

As a further modification, the paper 90a from roll 90 is rolled up as the trowel moves on a roll 109 located on the back of the trowel near its trailing edge, as indicated in Figs. 9 and 10. Such a method is of advantage where it is desired to use the paper for the purpose of imprinting a characteristic impression on the wall surface, and where it is not desirable to leave the paper in contact with the wall surface while the wall dries. It will be evident that this roll of paper or the roll as used in Figs. 7 and 8, may be used 70

75 to carry tile or other particles which it is de-

sired to embed in the plaster or cement surface of the wall, such particles simply being pasted or secured in any easily detachable manner on the surface of the paper before rolling it up.

It has previously been described that in some instances the trowel members may not be moved until the wall material is partially or wholly set, and in such instances, of course, there is no occasion for moving the trowels in the plane of the wall surface. Such a method is particularly applicable in connection with use of a flexible sheet in the plane of the wall surface, backed up by the trowel member. In such an operation, the wall surface is formed by the texture of the sheet, and the trowel member may not be moved 10 for the purpose of finishing the surface, but may be allowed to stand until the wall material is partially or wholly set, as heretofore described. Thus the trowel members may either have the dual function of backing-up member and traveling finishing member, or, especially in case of use of the flexible sheet, simply the function of backing-up member. The expression trowel as herein defined denotes the members 30 whether said members have both functions, i. e., backing-up 20 and smoothing, or only the single function of backing-up, and it will therefore be understood that usage of the expression trowel does not, within the meaning herein adopted, denote or imply travel in the plane of the wall surface, and 30 that such travel is not necessarily present unless expressly specified.

Fig. 11 shows a modification in which both surfaces of a wall are troweled or finished simultaneously. This method is particularly useful in constructing solid walls, but may also be used to form reenforced or cored walls. Fig. 11 shows a wall 105 being constructed in accordance with this method. Two trowels 30 are used, one for each surface of the wall, and are moved along as the wall is built, the plaster or cement being placed between the trowels. The trowels are moved to keep up with the plastering operation in the same manner as with the single trowel method previously described. Each trowel is 40 provided at the bottom with a roller 106 and track 107, and at its back, near its top, with a roller 108 engaging in a track 109 supported by false work 110. As here shown the upper roller is mounted on a vertical axis, and is engaged on 50 both sides by the flanges of the track, which is of channel shape, with its channel facing upwardly. Thus the upper track and roller not only holds the trowel up to the work, but also prevents it from tilting inwardly beyond the exterior 55 surface of the wall to be formed. It will be evident that this type of roller and track may be used with the trowel of Figs. 3 and 4, if desired.

I have now illustrated my invention by way of giving a somewhat detailed description of typical equipment for carrying it into effect; it is to be understood, however, that various changes in design, structure and arrangement of such equipment as well as modifications in the method of use of the equipment, may be made without departing from the spirit and scope of the invention or of the appended claims.

I claim:

1. The method of forming a plaster or cementitious wall that is comparatively thick relative 70 to its height, that comprises placing a comparatively large surfaced trowel member in the plane of the outer surface of the wall to be constructed, placing the wall material in a wet state against said trowel from the rearward side of the wall 75

- to be constructed, said trowel serving as a backing for the wet material as said material is placed in position, and moving said trowel to keep it abreast of the material as placed and to finish the outer surface of said material.
2. The method of forming a wall of plaster or cementitious material about an openwork reinforcing frame, that comprises placing a comparatively large surfaced trowel member in the plane of the outer surface of the wall to be constructed, impacting the wall material in a wet state against said trowel from the rearward side of the wall to be constructed, said trowel serving as a backing for the wet material as said material is placed in position, and moving said trowel to keep it abreast of the material as placed and to finish the outer surface of said material.
3. Means for forming a wall of plaster or cementitious material, comprising a comparatively large surfaced trowel having a finishing surface, means for guiding and supporting said trowel in a substantially upright position for linear movement with its finishing surface traveling in the plane of the exterior surface of the wall to be constructed, and means for impacting the wall material in a wet state against the finishing surface of the trowel.
4. Means for forming a wall of plaster or cementitious material, comprising a comparatively large trowel having a finishing surface, and having a mold section extending thereacross, means for guiding and supporting said trowel in a substantially upright position for linear movement parallel to the direction of said mold section and with its finishing surface traveling in the plane of the exterior surface of the wall to be constructed, said finishing surface being adapted to back up the plaster or cementitious material placed to form the wall and to finish the exterior surface of said material by movement on its guiding means.
5. Means for forming a wall of plaster or cementitious material, comprising a comparatively large surfaced trowel member, means for supporting said trowel member in a substantially upright position with its front surface in the plane of the exterior surface of the wall to be constructed, a flexible sheet supported in said plane in contact with the front surface of said trowel member, and means for impacting the wall material in a wet state against said flexible sheet at places backed up by said trowel member.
6. Means for forming a wall of plaster or cementitious material, comprising a comparatively large trowel member embodying a plurality of contiguous sections and means for securing said sections together, means for supporting said trowel in a substantially upright position with said sections in the planes of the exterior surfaces of the wall to be constructed, and a flexible sheet positioned in contact with at least one of said trowel sections, whereby wet material may be impacted against said sheet backed up by said trowel section.
7. The method of forming a wall of plaster or cementitious material about openwork reinforcing means, that comprises placing two comparatively large surfaced trowel members in the planes of the two surfaces of the wall to be constructed, impacting the wall material in a wet state between said trowels, said trowels serving as backings for the material as it is placed in position, and moving said trowels to keep them abreast of the material as placed.
8. The method of forming a wall of plaster or cementitious material about an openwork reinforcing frame, that comprises stretching a flexible sheet in the plane of the outer surface of the wall to be constructed, impacting the wall material in a wet state against the inside surface of said flexible sheet, and placing a backing-up member which is comparatively large but is of lesser area than said flexible sheet in supporting relation to the outer surface of said sheet at places where the wet material is being impacted against said sheet.

MARCUS M. CORY.
